(57) CLAIM

The ornamental design for a flat hair clip, as shown and described.

DESCRIPTION

[FIG. 1 is a perspective view of a first embodiment of a flat hair clip according to the present design.]

[FIG. 2 is a front elevation view thereof.]

[FIG. 4 is a left side elevation view thereof.]

FIG. 8 is a perspective view of [a second embodiment of] a flat hair clip according to the present design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top view thereof.

FIG. 14 is a bottom view thereof.

FIG. 15 is a perspective view of a third embodiment of a hair clip with open sides according to the present design.]

[FIG. 16 is a front elevation view thereof.]

[FIG. 17 is a rear elevation view thereof.]

[FIG. 18 is a left side elevation view thereof.]

[FIG. 19 is a right side elevation view thereof.]

[FIG. 20 is a top view thereof; and,]

[FIG. 21 is a bottom view thereof.]

(Amended)

The broken lines in the drawings depict portions of the flat hair clip that form no part of the claimed design.

1 Claim, 21 Drawing Sheets

Matter enclosed in heavy brackets [ ] appears in the original patent but forms no part of this reissue; matter printed in italics indicates the additions made by reissue.
